US00D736189S

(12) **United States Design Patent**
Cooper et al.

(10) **Patent No.:** US D736,189 S
(45) **Date of Patent:** ** Aug. 11, 2015

(54) **MOUNT**

- (71) Applicant: **Freedman Electronics Pty. Ltd.**, Silverwater, NSW (AU)
- (72) Inventors: **Peter Noel Cooper**, Bronte (AU); **Sun Kyung Sunwoo**, Denistone (AU); **David Anthony Pidcock**, Freshwater (AU)
- (73) Assignee: **Freedman Electronics Pty. Ltd.** (AU)
- (**) Term: **14 Years**
- (21) Appl. No.: **29/480,875**
- (22) Filed: **Jan. 30, 2014**
